(57) **CLAIM**

The ornamental design for a cover head for a bathroom rack support, as shown and described.

DESCRIPTION

FIG. 1 is a perspective view of the cover head for a bathroom rack support showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a cover head for a bathroom rack support, with a towel rack and toilet paper roll shown in broken lines for illustrative purposes only and forming no part of the claimed design.
